LIGHTING FIXTURES

Marvin Dworkin, Highland Park, and Robert S. Fremont, Wilmette, Ill., assignors to Halo Lighting, Inc., Chicago, Ill.

Filed Aug. 2, 1963, Ser. No. 299,541
7 Claims. (Cl. 240—78)

This invention relates to improvements in lighting fixtures and more particularly to a recessed lighting fixture.

One of the objects of this invention is to provide a recessed lighting fixture with a slidable lens or panel which is readily slidable from a position under the light bulb to a position laterally thereof to expose the light bulb for access thereto.

In recessed lighting fixtures it is desirable that the light bulb be enclosed and yet that there be access to it when it is necessary to replace it or for other necessary repairs. The present invention accomplishes the foregoing in a very simple and inexpensive structure whereby access to the light bulb may be readily obtained and wherein the light bulb is enclosed in normal operation.

Other objects will become apparent as this description progresses.

In the drawings:

FIG. 1 is a view of the recessed lighting fixture of this invention mounted in the ceiling.

FIG. 2 is a sectional view taken on line 2—2 of FIG. 1.

FIG. 3 is a view taken on lines 3—3 of FIG. 1.

FIG. 4 is a view of the sliding member, and

FIGS. 5 and 6 are fragmentary perspective views taken on lines 5—5 and 6—6 respectively of FIG. 4.

The invention includes a generally rectangular-shaped housing generally indicated at 10, which includes a top wall 12 and a bottom wall 14 spaced therefrom and parallel thereto, connected by spaced side walls 16 and an end wall 18, all of which are welded or brazed together to form an integral housing. The opposite end 19 of the housing is closed. The side walls 16 are bent to form outwardly extending lower flanges 20 with spaced openings 21 therein. The flanges 20 rest on the top interior face of the ceiling 22 and are secured thereto by fastening elements 24 which secure the entire structure in position in the recessed portion of the ceiling, as is well understood in the art.

The top wall 12 is provided with an enlarged opening 26 adjacent one end thereof, the diameter of which is slightly less than the length of the housing. The top wall is shaped to provide a downwardly extending annular lip or flange 27 surrounding said opening. Spaced upwardly extending ears 28 are struck from the top wall.

A cylindrical-shaped bulb housing generally indicated at 30 has its lower end positioned within the flange 27 and is secured to the ears 28 by suitable fastening elements 32, such as screws. The lower end of the cylindrical housing 30 is open and extends partially into the interior of the rectangular-shaped housing. The top of the cylindrical bulb housing 30 is closed by a cover plate 34 welded thereto.

The bottom wall 14 has an opening 36 in alignment with the upper opening 26. A downwardly extending annular flange or lip 38 surrounds the opening 36. A conventional lamp socket 40 is supported on the cover plate 34. A metal conduit 42 leads from said socket 40 to a junction box 44 mounted on the top wall 12 of the housing 10. The conductor wire extends inside the conduit from the junction box to the socket. A light bulb 46 is secured in said socket. The reflector 48 is loosely supported inside the cylindrical housing 30 on a plurality of spaced fingers 50 fixedly secured to the housing 30. The fingers 50 have upturned ends 51. The reflector 48 has

2

an opening at the top thereof to accommodate the light bulb.

Supported within the rectangular-shaped housing is a slidable member generally indicated at 52, best shown in FIG. 4, which supports the lens. The slidable member includes a plate 54 of generally square-shape having its opposite sides turned down to form side supporting legs 56. The plate is shaped to provide an annular upstanding flange 57 which surrounds the central opening 58 of the plate. A removable ring generally indicated at 60 is supported in the opening 58 of the slidable member 52. The ring has an annular upstanding flange 62 and is provided with spaced fingers 64 for securing a lens 66 which is supported on the ring. The term "lens" includes any member which acts to cover the opening and which permits the light rays to pass therethrough. It may be any translucent or transparent pane or panel.

The ring with the lens is removably secured to the plate 54 of the slidable member 52 by providing an extension 67 on the underside of the ring 60 which slides into a depressed strap portion 68 in the plate. The ring also has a similarly shaped extension 69 diametrically opposite the extension 67, with a bayonet slot 70 for engagement with a screw 71 secured to the plate. The ring 60, together with the lens 66 therein, may be removed by loosening the screw 71 to permit a drop down of the ring so that it can be shifted laterally to permit the extension 67 to be slid out of the strap 68.

The slidable lens supporting member 52 is manually slidable as a unit in the rectangular shaped housing 10 from a position under the cylindrical housing 30 and the light bulb 46 to the side best shown in full lines in FIG. 3, where it is slid laterally into the portion of the housing positioned away from the cylindrical housing. The end wall 18 of the housing limits its sliding movement in one direction while an upturned flange 74 on the lower wall at the open end 19 limits sliding movement in the opposite direction. The slidable member 52 may be slid very easily in either direction by manually engaging the lens or any exposed portion of the slidable member and moving it laterally. The parts fit freely and movement is relatively easy.

When the slidable lens holder or member 52 is positioned in alignment with the openings 26 and 28, which is the normal operating position, the light from the light bulb will pass through the lens 66 and in this position the interior of the cylindrical housing is not visible and is not accessible. However, as the slidable holder is slid laterally to that shown in full lines in FIG. 3, the interior of the cylindrical housing is exposed for access thereto and the light bulb may be replaced or other work done to the unit.

As best seen in FIG. 1, only the interior of the cylindrical housing is exposed to view. The rectangular housing 10 is completely hidden from view at all times by virtue of its mounting in the ceiling. The annular flange or lip 38 of the rectangular housing extends through an annular opening 25 formed in the ceiling and terminates flush with the exposed ceiling surface. A trim ring generally indicated at 74 is inserted inside and held by the annular flange 38 for the purpose of providing a finished or ornamental appearance to the opening. The trim ring 74 has a conically-shaped body 76 which terminates in an annular outwardly extending flange 78. A plurality of resilient fingers 80 extend outwardly from the conically-shaped body 76 and releasably engages the bottom wall 14 of the housing adjacent the opening to hold the trim ring 74 in position, as shown in FIG. 2.

It will be understood that various changes and modifications may be made from the foregoing without departing from the spirit and scope of the appended claims.

What is claimed is:

1. A ceiling lighting fixture, said fixture including a generally rectangular-shaped first housing horizontally positioned on or in the ceiling, said housing having horizontally extending aligned openings with one opening in the top wall and the other opening in the bottom wall, a second housing secured to said first housing in alignment with said openings and extending vertically upwardly of said first housing for supporting a light bulb therein, a horizontally positioned slidable member supported in said first housing and adapted to be manually slid horizontally in said housing from a position under said second housing to a position substantially laterally of said second housing.

2. A structure defined in claim 1 in which the slidable member supports a lens.

3. A structure defined in claim 1 in which the slidable member supports a covering member which closes the opening in the bottom wall of the first housing but which permits the light rays to pass through.

4. A structure defined in claim 1 in which the portion of the first housing extending laterally of the second housing is positioned above the ceiling and hidden from view.

5. A structure defined in claim 1 in which the diameter of the opening in the bottom wall is substantially one-half the length of the first housing.

6. A lighting fixture comprising a horizontally posi-

5
10

tioned first housing positioned on or in the ceiling, said housing having an upper horizontal wall and a lower horizontal wall with an opening in each wall with said openings vertically aligned, a second housing secured to said first housing in alignment with said openings and extending vertically upward of said first housing for supporting a light bulb therein, said first housing having means extending horizontally and laterally thereof, a horizontally positioned slidable member supported by said first housing and adapted to be manually slid horizontally from said first housing into said means extending horizontally and laterally thereof.

7. A structure defined in claim 6 in which the slidable member supports a lens.
